United States Patent Office

Des. 201,076
Patented May 11, 1965

201,076

TRAILER

Le Roy K. Patnode, 2011 Alba Road, Ben Lomond, Calif.

Filed May 27, 1964, Ser. No. 80,177

Term of patent 14 years

(Cl. D14—3)

FIG. 1.

FIG. 2.

FIG. 3.

FIG. 4.

FIG. 5.

FIG. 1 is a top plan view of a trailer showing my new design;

FIG. 2 is an elevational view of one side thereof;

FIG. 3 is an elevational view of the other side opposite said one side;

FIG. 4 is a front elevational view; and

FIG. 5 is a rear elevational view.

The dominant features of my design reside in the portions shown in full lines.

I claim:

The ornamental design for a trailer, as shown and described.
